US00D887363S

(12) **United States Design Patent** (10) Patent No.: **US D887,363 S**
Byrne et al. (45) Date of Patent: **** Jun. 16, 2020**

(54) **ELECTRICAL POWER UNIT**

(71) Applicants: **Norman R. Byrne**, Ada, MI (US);
Joseph D. Ward, Grand Rapids, MI (US)

(72) Inventors: **Norman R. Byrne**, Ada, MI (US);
Joseph D. Ward, Grand Rapids, MI (US)

(**) Term: **15 Years**

(21) Appl. No.: **29/634,765**

(22) Filed: **Jan. 24, 2018**

(51) LOC (12) Cl. **13-03**

(52) U.S. Cl.

USPC **D13/139.4**

(57) **CLAIM**

The ornamental design for an electrical power unit, as shown and described.

DESCRIPTION

FIG. 1 is a top-front perspective view of an electrical power unit showing our new design;

FIG. 2 is a bottom-front perspective view thereof;

FIG. 3 is a top-rear perspective view thereof;

FIG. 4 is bottom-rear perspective view thereof;

FIG. 5 a front elevation thereof;

FIG. 6 is a rear elevation thereof;

FIG. 7 is a top plan view thereof;

FIG. 8 is a bottom plan view thereof;

FIG. 9 is a right side elevation thereof; and,

FIG. 10 is a left side elevation thereof.

The broken lines in the drawings are for the purposes of illustrating portions of the electrical power unit that form no part of the claimed design.

1 Claim, 4 Drawing Sheets
